DESIGN FOR A GOLF CLUB HEAD

James Gourlay, Glencoe, Ill.

Application March 9, 1935, Serial No. 55,796

Term of patent 7 years

To all whom it may concern:

Be it known that I, James Gourlay, a citizen of the United States, residing at Glencoe, in the county of Cook and State of Illinois, have invented a new, original, and ornamental Design for a Golf Club Head, of which the following is a specification, reference being made to the drawing, forming a part thereof.

In the annexed drawing,

Fig. 1 is a fragmentary end elevation of a golf club head embodying my invention;

Fig. 2 is a back face elevation of the golf club head;

Fig. 3 is an edge view of the golf club head, the same being taken looking toward the sole of the golf club head.

I claim:

The ornamental design for a golf club head as shown.

JAMES GOURLAY.
